TAKE-UP DEVICE FOR KNITTING MACHINES

Fritz Lambach, Tenafly, N. J., assignor to Robert Reiner, Inc., Weehawken, N. J.

Application April 14, 1950, Serial No. 155,847

29 Claims. (Cl. 66—149)

1

This invention relates to knitting machines, and more particularly to a take-up device for taking up the fabric knitted by the knitting implements of a knitting machine.

An object of the present invention is to provide a take-up device which facilitates the threading of the fabric at the beginning of a knitting operation.

Another object of the present invention is to provide a take-up device of a knitting machine which subjects the fabric delivered by the knitting implements to a substantially constant tension, so that the quality of the fabric is maintained during the operation of the knitting machine.

A further object of the present invention is to provide a take-up device of a construction eliminating slippage between a power-driven take-up roller and the fabric delivered by the knitting implements of the knitting machine.

Another object of the present invention is to provide a take-up device arrangement which permits a continuation of the knitting operation of the knitting machine while fabric is wound-off from a full wind-up roller remaining in the knitting machine during the winding-off of the fabric.

A further object of the present invention is to provide a mechanism facilitating the winding-off of fabric from a full wind-up roller.

Another object of the present invention is to improve on the art of knitting machines as now ordinarily made.

Other objects and structural details of the invention will be apparent from the following description when read in conjunction with the accompanying drawings forming part of this specification, wherein:

Fig. 1 is a fragmentary top plan view of a take-up device according to the invention, some parts being broken away;

Fig. 2 is a side elevational view of the left hand end of the take-up device shown in Fig. 1;

Fig. 3 is a sectional view taken along line III—III of Fig. 2;

Fig. 4 is a sectional view taken along line IV—IV of Fig. 3;

Fig. 5 is a sectional view similar to that shown in Fig. 4, wherein, however, the guiding roller of the take-up device is in its inactive position, and

Fig. 6 is a sectional view taken along line VI—VI of Fig. 3.

The drawings illustrate as an example the application of a take-up device to a warp knit-

ting machine of which only those parts are shown, which are necessary for the understanding of the invention.

Referring now to the drawings, 10 indicates the left hand end frame and 12 indicates the right hand end frame of a warp knitting machine.

As best shown in Figs. 1—3, a shaft 14, operatively connected in a suitable manner with the power-driven main shaft of the knitting machine, carries a sprocket wheel 16 at its end. Said sprocket wheel 16 is connected through a chain 18 with a sprocket wheel 20 keyed to the driven shaft 22 of a reduction gear 24 mounted on a bracket 26 secured to the end frame 10 of the knitting machine.

The hollow end portion of the output shaft 28 receives a stud 30 of a take-up roller 32 extending longitudinally of the knitting machine. Preferably said take-up roller 32 is provided with a friction covering of suitable material, for example, rubber, felt, a rubber-cork composition, etc. The stud 30 operatively connected with the output shaft 28 by a pin 34 is journaled in a bearing 36 of the end frame 10. A stud 38 (see Fig. 1) at the other end of the take-up roller 32 is journaled in a bearing 40 of the end frame 12 of the knitting machine. Thus, the take-up roller 32 is rotatably mounted on the frame of the knitting machine and may be rotated by the main shaft of the knitting machine through the medium of the chain drive 16, 18, 20 and the reduction gear 24.

As best shown in Figs. 2 and 3, a sprocket wheel 42 is rigidly connected with the stud 30 of the take-up roller 32 by means of a pin 44. Additional sprocket wheels 46 and 48 are keyed to the projecting ends of shafts 50 and 52 respectively, which are journaled in bearings 54 and 56 respectively, of a bracket 58 secured to the end frame 10 of the knitting machine. Frictional driving rollers 60 and 62 respectively are keyed to the other ends of the shafts 50 and 52 respectively. A tensioning sprocket wheel 64 is carried by a shaft 66 adjustably mounted in the bracket 58. An endless chain 68 is trained around the sprocket wheels 42, 46, 64 and 48, so that, apparently, the frictional driving rollers 60 and 62 are rotated simultaneously with a rotation of the take-up roller 32 by means of the main shaft through the medium of the chain drive 16, 18, 20 and the reduction gear 24.

As best shown in Fig. 1, a similar bracket 70 is secured to the end frame 12. Supporting rollers 72 and 74 are rotatably mounted on said bracket 70.

Both brackets 58 and 70 are provided with projections 76 and 78 respectively having cut-outs 80 and 82 respectively. Said cut-outs 80 and 82 are arranged for shiftably receiving the studs 34 and 36 of a wind-up roller 88 extending longitudinally of the machine. Said wind-up roller 88 has a flange 90 and 92 respectively at each of its end portions. In the positions shown in Figs. 1, 2 and 3, the flange 90 is engaged with the frictional driving rollers 60 and 62 resting thereon. Likewise the flange 92 shown in Fig. 1 rests on the supporting rollers 12 and 14. It will be readily understood that the frictional driving rollers 60 and 62 rotated by the mechanism described above, rotate the wind-up roller 88 when the flange 90 is engaged with said frictional driving rollers 60 and 62.

For a purpose to be described hereinafter, the flange 90 of the wind-up roller 88 may be disengaged from the frictional driving rollers 60 and 62 by means of a lifting lever 94, swingably mounted on the bracket 58 at 36. Said lifting lever 94 has an arm 98 for manual operation of the lever, and an arm 100 carrying a pair of rollers 102 and 104 rotatably mounted thereon. When the lifting lever 94 is in the position shown in Fig. 2, the rollers 102, 104 are out of engagement with the stud 84 of the wind-up roller 88, so that the flange 90 can rest on the frictional driving rollers 60 and 62 for frictional engagement therewith. If, however, the lifting lever 94 is swung by hand into the position shown in Fig. 6, which is limited by an abutment of an adjustable abutting screw 105 against the bearing 58, the rollers 102 and 104 are brought into engagement with the stud 84 of the wind-up roller 88, whereby the latter is lifted to a slight extent, sufficient for disengagement of the flange 90 from the frictional driving rollers 60 and 62. In said position of the lifting lever 94, the stud 84 is supported by the rollers 102 and 104. When the wind-up roller 88 is in the position shown in Fig. 6 with its flange 90 disengaged from the frictional driving rollers 60, 62, the wind-up roller 88 may be readily rotated by hand, and the rotation of the power-driven frictional driving rollers 60, 62 has no influence on the wind-up roller 88.

As best shown in Figs. 1, 2, and 3, a supporting member 108 substantially in the shape of a disc, is rotatably arranged on the enlarged portion 110 of the stud 38 of the take-up roller 32. Said supporting member 108, which may be freely rotated, by hand, relative to the stud portion 110, may be held in an adjusted position by means of a spring-loaded pin 112 arranged on the end frame 10 for selective engagement with one of the bores 114 and 116 (see Fig. 2), arranged on the rim of said supporting member 108. A gear 118 arranged adjacent to the hub of the settable supporting member 108 is rigidly connected with the stud portion 110 of the take-up roller 32 by means of a pin 120.

As best shown in Fig. 1, a disc-like supporting member 122 is rotatably arranged on the other stud 38 of the take-up roller 32 at the other end thereof. Said supporting member 122 may also be freely rotated by hand relative to the stud 38 of the take-up roller 32. Furthermore, the supporting member 122 may be held in an adjusted position by a spring-loaded pin 124 arranged in the end frame 12 of the machine. Furthermore a gear 126 is rigidly connected with the stud 38 by means of a pin 128. The hub of the disc-like supporting member 122 abuts at one of its ends against said gear 126 and at its other end against

a spacing collar 130 arranged on the stud 38 whereby the supporting member 122 is prevented from axial displacement.

As best shown in Figs. 2 and 3 the stud 132 of a guiding roller 134, extending longitudinally of the machine, is journalled in a ball bearing 136 set in a boss 138 of the disc-like supporting member 108. Preferably said guiding roller 134 is provided with a friction covering of suitable material, for example, rubber, felt, a rubber-cork composition, etc. A gear 140 in mesh with the gear 118 of the take-up roller 32 is rigidly connected with the stud 132 of the guiding roller 134 by a pin 142. As best shown in Fig. 1, a stud 144 arranged at the other end of the guiding roller 134 is rotatably mounted, preferably through the medium of a ball bearing, in a boss 146 of the supporting member 122. Moreover, a gear 148 in mesh with the gear 126 of the take-up roller 32 is rigidly connected with the stud 144 of the guiding roller 134.

As will be readily understood from above, a rotation of the take-up roller 32 by means of the power-driven main shaft through the medium of the chain drive 16, 18, 20 and the reduction gear 24 results in a rotation of the guiding roller 134 about its axis by means of the pairs of meshing gears 118, 140 and 126, 148.

Furthermore, the arrangement of meshing gears 118, 140 and 126, 148 at both ends of the comparatively long take-up roller 32 and guiding roller 134 reduces the twisting of said rollers to a minimum during a setting operation of the guiding roller 134 by a rotation of the supporting members 108 and 122 from the active position of the guiding roller 134 shown in Fig. 4 into the inactive position of said guiding roller shown in Fig. 5, and vice versa.

The operation of the take-up device is as follows:

Prior to the start of the knitting machine the supporting members 108 and 122 are brought into such a position by manual rotation around the longitudinal axis of the take-up roller 32, that the guiding roller 134 is in the inactive position above the take-up roller 32 as shown in Fig. 5. The guiding roller 134 is held in said inactive position by the engagement of the holding pin 112 (Fig. 1) with the bore 116 (see Fig. 5). The holding pin 124 (Fig. 1) at the other end of the machine is in engagement with a corresponding bore of the supporting member 122.

After the setting of the guiding roller 134 into the position shown in Fig. 5, the knitting machine is started. Fabric 150 knitted by the knitting implements 152 may be readily threaded in the take-up device. The fabric 150 is passed through the space between the guiding roller 134 and the take-up roller 32. When a sufficient length of fabric 150 has been knitted, the fabric is connected with the wind-up roller 88 in any suitable manner. Now the fabric 150 contacts a slight portion of the take-up roller 32. The power-driven take-up roller 32 and the power-driven wind-up roller 88 draw the fabric 150 from the knitting implements 152. After a certain length of fabric 150 has been wound on the wind-up roller 88, the lifting lever 94 is swung from the position shown in Fig. 2 into the position shown in Fig. 6 without interruption of the operation of the knitting machine. After the flange 90 of the wind-up roller 88 has been disengaged by said actuation of the lifting lever 94 from the driving rollers 60 and 62, the holding pins 112 and 124 are disengaged from the bores of the supporting members 108 and 122

by pulling same outwardly against the action of their springs. As a matter of convenience each of said holding pins 112 and 124 may be temporarily held in its disengaged position by turning same slightly after disengagement of its safety pin 154 and 156 respectively from the associated slot in the hub receiving the holding pin. After disengagement of the holding pins from the bores in the supporting members 108 and 122, the latter together with the guiding roller 134 may be turned around the longitudinal axis of the take-up roller 32 in the direction of the arrow A shown in Fig. 5, until the bore 114 of the supporting member 108 reaches the position formerly occupied by the bore 116 in alignment with the associated holding pin. Said position is shown in Figs. 1-4. Thereafter the holding pins 112 and 124 are brought into engagement with the bore 114 of the supporting member 108 and with the corresponding bore of the supporting member 122, so that now the guiding roller 134 is held in the position shown in Figs. 1-4. As will be readily understood from the comparison of Fig. 5 with Fig. 4 during said setting of the supporting members 108 and 122 from the position shown in Fig. 5 into the position shown in Fig. 4, the guiding roller 134 has been moved through an angle of 270° around the longitudinal axis of the take-up roller 32. During said angular displacement of the guiding roller 134 the guiding roller is brought into contact with the fabric 150, a portion of which now is wound off from the wind-up roller 88, which may be freely rotated, as its flange 90 has been disengaged from the driving rollers 60 and 62 by the lifting lever 94, as shown in Fig. 6. As best shown in Fig. 4, said angular displacement of the guiding roller 134 into its active position causes a contact of the fabric 150 with the take-up roller 32 over a substantial portion of the circumference of the latter. Likewise the fabric contacts a substantial portion of the circumference of the guiding roller 134. According to the embodiment shown in Fig. 4, the contact between the fabric and the take-up roller, as well as between the fabric and the guiding roller amounts to approximately 270° in each case. The guiding roller 134 now is below the path of the fabric 150 extending between the knitting implements and the take-up roller 32.

After the guiding roller 134 has been set in the active position shown in Figs. 1-4, the lifting lever 94 is returned from the position shown in Fig. 6 into the position shown in Fig. 2, whereby the flange 90 of the wind-up roller 88 is re-engaged with the frictional driving rollers 60 and 62, so that now the wind-up roller 88 is driven for winding up the fabric.

The looping of the fabric 150 around the take-up roller 32 and guiding roller 134 in the manner shown in Fig. 4 prevents slippage between the fabric and said rollers, so that the tension exerted on the fabric remains constant and the quality of the knitted fabric is maintained during the operation of the machine.

When the wind-up roller is full, the fabric may be cut at a suitable place between the guiding roller 134 and the wind-up roller and the latter may again be lifted by the lifting lever 94 for disengagement of its flange 90 from the driving rollers 60 and 62. Now the fabric may be pulled from the wind-up roller 88 by hand and placed in a suitable container. During said pulling of the fabric from the wind-up roller 88 the knitting operation of the knitting machine continues. The location of the guiding roller 134 in its active po-

sition shown in Fig. 4 provides for sufficient grip on the fabric and tension exerted on the latter for drawing the fabric from the knitting implements. After the wind-up roller 88 has been emptied, the free end of the fabric is connected with the wind-up roller 88, as soon as a sufficient length of fabric has been knitted during the continuation of the knitting operation. After the connection of the fabric with the wind-up roller 88, the flange 90 of the latter is re-engaged with the driving rollers 60 and 62 by a return of the lever 94 into the position shown in Fig. 2 for driving the wind-up roller 88 by the power drive.

Of course, if desired, a full wind-up roller may be removed from the knitting machine after the fabric has been cut and may be replaced by a fresh empty wind-up roller. In such a case the knitting machine should be stopped and the guiding roller should be returned into its inactive position shown in Fig. 5, whereupon the threading of the fabric and the connection thereof with the empty wind-up roller takes place in the manner described above.

I have described a preferred embodiment of my invention, but it is understood that this disclosure is for the purpose of illustration and that various omissions and changes in shape, proportion and arrangement of parts as well as the substitution of equivalent elements for those herein shown and described, may be made without departing from the spirit and scope of the invention as set forth in the appended claims.

For example, either one of the pairs of meshing gears 118, 140 and 126, 148, or both pairs of said meshing gears, connected with the take-up rollers 32 and guiding roller 134 respectively, may be omitted, if so desired.

Furthermore, the rotatable guiding roller 134 could be replaced by a guiding rod rigidly connected with the supporting member 108 and 122.

Furthermore, the supporting members must not necessarily be in the shape of discs concentrically arranged with respect to the longitudinal axis of the take-up roller 32. If desired, the means for setting the guiding roller 134, or a guiding rod substituted therefor, in an inactive position and in an active position could be of different construction and arrangement.

Moreover, if so desired, a duplicate of the lifting lever 94 could also be arranged on the bracket 70 at the other end of the knitting machine for disengaging the flange 90 from the idle supporting rollers 72 and 74.

What I claim is:

1. A take-up device for taking up the fabric knitted by the knitting implements of a knitting machine, comprising in combination: a take-up roller rotatably mounted on the knitting machine for frictional contact at its circumference with fabric delivered by the knitting implements of the knitting machine, a drive for rotating said take-up roller at a circumferential speed substantially equal to the travelling speed of said fabric, a wind-up roller rotatably mounted on the knitting machine for winding-up the fabric after its contact with said take-up roller, driving means for rotating said wind-up roller, guiding means extending substantially parallel to said take-up roller, said guiding means being movably mounted on said knitting machine for movement around said take-up roller so as to be settable in various positions relative to said take-up roller, in an inactive position said guiding means being out of contact with said fabric, in an active position said guiding means contacting said fabric and guid-

ing same around a substantial portion of the circumference of said take-up roller, and setting means for setting said guiding means in one of said two positions.

2. A take-up device for taking up the fabric knitted by the knitting implements of a knitting machine, comprising in combination: a take-up roller rotatably mounted on the knitting machine for frictional contact at its circumference with fabric delivered by the knitting implements of the knitting machine, a drive for rotating said take-up roller at a circumferential speed substantially equal to the travelling speed of said fabric, a wind-up roller rotatably mounted on the knitting machine for winding up the fabric after its contact with said take-up roller, driving means for rotating said wind-up roller, guiding means extending substantially parallel to said take-up roller, said guiding means being movably mounted on said knitting machine for movement around said take-up roller so as to be settable in various positions relative to said take-up roller, in an inactive position said guiding means being out of contact with said fabric, in an active position said guiding means contacting said fabric and looping same at first around a substantial portion of the circumference of said take-up roller and thereafter around itself, and setting means for setting said guiding means in one of said two positions.

3. In a take-up device as claimed in claim 1, said guiding means training said fabric around at least half of the circumference of said take-up roller when it is in said active position.

4. In a take-up device as claimed in claim 1, said guiding means being of cylindrical shape, and said guiding means training said fabric around a substantial portion of the circumference of said take-up roller and of its own circumference when it is set in said active position.

5. In a take-up device as claimed in claim 1, said guiding means being of cylindrical shape, and said guiding means training said fabric around at least one half of the circumference of said take-up roller and around at least one half of its own circumference when it is set in said active position.

6. A take-up device for taking up the fabric knitted by the knitting implements of a knitting machine, comprising in combination: a take-up roller rotatably mounted on the knitting machine for frictional contact at its circumference with fabric delivered by the knitting implements of the knitting machine, a drive for rotating said take-up roller at a circumferential speed substantially equal to the travelling speed of said fabric, a wind-up roller rotatably mounted on the knitting machine for winding-up the fabric after its contact with said take-up roller, driving means for rotating said wind-up roller, supporting means movably mounted on said knitting machine, said supporting means being settable in a first position and in a second position, setting means associated with said supporting means for setting same in one of said two positions, and a guiding element carried by said supporting means for movement around said take-up roller, said guiding element being in an inactive position out of contact with said fabric when said supporting means is in said first position, and said guiding element being in an active position contacting said fabric and guiding same around a substantial portion of the circumference of said take-up roller when said supporting means is in said second position.

7. A take-up device for taking up the fabric knitted by the knitting implements of a knitting machine, comprising in combination: a take-up roller rotatably mounted on the knitting machine for frictional contact at its circumference with fabric delivered by the knitting implements of the knitting machine, a drive for rotating said take-up roller at a circumferential speed substantially equal to the travelling speed of said fabric, a wind-up roller rotatably mounted on the knitting machine for winding up the fabric after its contact with said take-up roller, driving means for rotating said wind-up roller, supporting means movably mounted on said knitting machine, said supporting means being settable in a first position and in a second position, setting means associated with said supporting means for setting same in one of said two positions, and a guiding element carried by said supporting means for movement around said take-up roller, said guiding element being in an inactive position out of contact with said fabric when said supporting means is in said first position, and said guiding element being in an active position contacting said fabric and looping same at first around a substantial portion of the circumference of said take-up roller and thereafter around itself when said supporting means is in said second position.

8. In a take-up device as claimed in claim 6, said guiding element training said fabric around at least one half of the circumference of said take-up roller when it is in said active position.

9. In a take-up device as claimed in claim 6, said guiding element being of cylindrical shape, and said guiding element training said fabric around a substantial portion of the circumference of said take-up roller and of its own circumference when it is set in said active position.

10. In a take-up device as claimed in claim 6, said guiding element being of cylindrical shape, and said guiding element training said fabric around at least one half of the circumference of said take-up roller and around at least one half of its own circumference when it is set in said active position.

11. A take-up device for taking up the fabric knitted by the knitting implements of a knitting machine, comprising in combination: a take-up roller rotatably mounted on the knitting machine for frictional contact at its circumference with fabric delivered by the knitting implements of the knitting machine, a drive for rotating said take-up roller at a circumferential speed substantially equal to the traveling speed of said fabric, a wind-up roller rotatably mounted on the knitting machine for winding-up the fabric after its contact with said take-up roller, driving means for rotating said wind-up roller, supporting means movably mounted on said knitting machine, said supporting means being settable in a first position and in a second position, setting means associated with said supporting means for setting same in one of said two positions, and a guiding roller carried by said supporting means for movement around said take-up roller, said guiding roller being rotatably mounted in said supporting means, said guiding roller being in an inactive position out of contact with said fabric when said supporting means is in said first position, and said guiding roller being in an active position contacting said fabric and guiding same around a substantial portion of the circumference of said take-up roller when said supporting means is in said second position.

12. In a take-up device as claimed in claim

11. a pair of coupling means, one of said coupling means being connected with said take-up roller, the other coupling means being connected with said guiding roller, and said coupling means being in operative engagement with each other when said guiding roller is in said active position.

13. In a take-up device as claimed in claim 6, said supporting means being rotatably mounted on said knitting machine in substantially coaxial alignment with said take-up roller, and said guiding element being eccentrically arranged on said supporting means and being above the path of said fabric when it is in the inactive position.

14. In a take-up device as claimed in claim 6, said supporting means being rotatably mounted on said knitting machine in substantially coaxial alignment with said take-up roller, said guiding element being eccentrically arranged on said supporting means and being above the path of said fabric when it is in the inactive position, and said guiding element being below the path of the fabric extending between the knitting implements and the take-up roller when said guiding element is in its active position.

15. In a take-up device as claimed in claim 6, said supporting means being rotatably mounted on said knitting machine in substantially coaxial alignment with said take-up roller, said guiding element being eccentrically arranged on said supporting means and being above the path of said fabric when it is in the inactive position, and said guiding element being substantially in the same horizontal plane as said take-up roller and below the path of the fabric extending between the knitting implements and the take-up roller when said guiding element is in its active position.

16. In a take-up device as claimed in claim 11, said supporting means being rotatably mounted on said knitting machine in substantially coaxial alignment with said take-up roller, and said guiding roller being eccentrically arranged on said supporting means and being above the path of said fabric when it is in the inactive position.

17. In a take-up device as claimed in claim 11, said supporting means being rotatably mounted on said knitting machine in substantially coaxial alignment with said take-up roller, said guiding roller being eccentrically arranged on said supporting means and being above the path of said fabric when it is in the inactive position, and said guiding roller being below the path of the fabric extending between the knitting implements and the take-up roller when said guiding roller is in its active position.

18. In a take-up device as claimed in claim 11, said supporting means being rotatably mounted on said knitting machine in substantially coaxial alignment with said take-up roller, said guiding roller being eccentrically arranged on said supporting means and being above the path of said fabric when it is in the inactive position, and said guiding roller being substantially in the same horizontal plane as said take-up roller and below the path of the fabric extending between the knitting implements and the take-up roller when said guiding roller is in its active position.

19. In a take-up device as claimed in claim 11, said supporting means being rotatably mounted on said knitting machine in substantially coaxial alignment with said take-up roller, said guiding roller being eccentrically arranged on said supporting means and being above the path of said fabric when it is in its inactive position, and a pair of coupling means, one of said coupling

means being connected with said take-up roller, the other coupling means being connected with said guiding roller, and said coupling means being in operative engagement with each other when said guiding roller is in said active position.

20. In a take-up device as claimed in claim 11, said supporting means being rotatably mounted on said knitting machine in coaxial alignment with said take-up roller, said guiding roller being eccentrically arranged on said supporting means and being above the path of said fabric when it is in its inactive position, and a pair of gears meshing with each other, one of said gears being connected with said take-up roller, and the other gear being connected with said guiding roller.

21. A take-up device for taking up the fabric knitted by the knitting implements of a knitting machine, comprising in combination: a take-up roller rotatably mounted on the knitting machine for frictional contact at its circumference with fabric delivered by the knitting implements of the knitting machine, a drive for rotating said take-up roller at a circumferential speed substantially equal to the travelling speed of said fabric, a wind-up roller rotatably mounted on the knitting machine for winding up the fabric after its contact with said take-up roller, driving means for rotating said wind-up roller, a pair of supporting members, one at each end of the knitting machine, said supporting members being rotatably mounted on said knitting machine in coaxial alignment with said take-up roller, a guiding roller rotatably mounted at its ends in said supporting members eccentrically to the axis of rotation of the latter, said supporting members being settable in a first position and in a second position, setting means associated with at least one of said supporting members for setting same in one of said two positions, said guiding roller being in an inactive position above the path of said fabric when said supporting members are in said first position, said guiding roller being in an active position contacting said fabric and guiding same around a substantial portion of the circumference of said take-up roller when said supporting members are in said second position, said active position of the guiding roller being located below the path of the fabric extending between the knitting implements and the take-up roller, and pairs of gears meshing with each other, one pair at each end of the knitting machine, one gear of each pair of gears being connected with said power-driven take-up roller, and the other gear of each pair of gears being connected with said guiding roller.

22. A take-up device for taking up the fabric knitted by the knitting implements of a knitting machine, comprising: a wind-up roller rotatably mounted on the knitting machine, a drive including frictional driving rollers, said wind-up roller being normally in operative engagement with said frictional driving rollers for rotation by the latter, a lifting lever swingably mounted on said knitting machine, and a pair of supporting rollers arranged on said lifting lever, said lifting lever being operable for bringing said supporting rollers into engagement with a portion of said wind-up roller so as to support the latter and lift same to a predetermined extent out of engagement with said frictional driving rollers.

23. A take-up device for taking up the fabric knitted by the knitting implements of a knitting machine, comprising in combination: a take-up

roller rotatably mounted on the knitting machine for frictional contact at its circumference with fabric delivered by the knitting implements of the knitting machine, a drive for rotating said take-up roller at a circumferential speed substantially equal to the traveling speed of said fabric, a wind-up roller rotatably mounted on the knitting machine for winding-up the fabric after its contact with said take-up roller, driving means for rotating said wind-up roller, said driving means being normally in operative engagement with said wind-up roller, a releasing mechanism operable for disengaging said wind-up roller from said driving means, guiding means extending substantially parallel to said take-up roller, said guiding means being movably mounted on said knitting machine for movement around said take-up roller so as to be settable in various positions relative to said take-up roller, in an inactive position said guiding means being out of contact with said fabric, in an active position said guiding means contacting said fabric and guiding same around a substantial portion of the circumference of said take-up roller, and setting means for setting said guiding means in one of said two positions.

24. In a take-up device as claimed in claim 23, said driving means including frictional driving rollers, said wind-up roller being normally in operative engagement with said frictional driving rollers, and said releasing mechanism including lifting means operable for lifting said wind-up roller to a predetermined extent so as to disengage same from said frictional driving rollers.

25. In a take-device as claimed in claim 23, said driving means including frictional driving rollers, said wind-up roller being normally in operative engagement with said frictional driving rollers, and said releasing mechanism including a lifting lever swingably mounted on said knitting machine and a pair of supporting rollers arranged on said lifting lever, said lifting lever being operable for bringing said supporting rollers into engagement with a portion of said wind-up roller so as to support the latter and lift same to a predetermined extent out of engagement with said frictional driving rollers.

26. In a take-up device as claimed in claim 23, said guiding means training said fabric around at least half of the circumference of said take-up roller when it is in said active position.

27. In a take-up device as claimed in claim 23, said guiding means being of cylindrical shape, and said guiding means training said fabric

around at least one half of the circumference of said take-up roller and around at least one half of its own circumference when it is set in said active position.

5 28. A take-up device for taking up the fabric knitted by the knitting implements of a knitting machine, comprising in combination: a take-up roller rotatably mounted on the knitting machine for frictional contact at its circumference with fabric delivered by the knitting implements of the knitting machine, a drive for rotating said take-up roller at a circumferential speed substantially equal to the travelling speed of said fabric, a wind-up roller rotatably mounted on the knitting machine for winding-up the fabric after its contact with said take-up roller, driving means for rotating said wind-up roller, said driving means being normally in operative engagement with said wind-up roller, a releasing mechanism operable for disengaging said wind-up roller from said driving means, supporting means movably mounted on said knitting machine, said supporting means being settable in a first position and in a second position, setting means associated with said supporting means for setting same in one of said two positions, and a guiding roller carried by said supporting means for movement around said take-up roller, said guiding roller being in an inactive position out of contact with said fabric when said supporting means is in said first position, and said guiding roller being in an active position contacting said fabric and guiding same around a substantial portion of the circumference of said take-up roller when said supporting means is in said second position.

29. In a take-up device as claimed in claim 28, said take-up roller being operatively connected with said guiding roller for rotating the latter when it is in its active position.
